UNITED STATES PATENT OFFICE

171,992

COMBINATION STEAM AND DRY IRON

Chauncey E. Waltman, Chicago, Ill., assignor to
Dominion Electric Corporation

Application December 16, 1953, Serial No. 28,109

Term of patent 14 years

(Cl. D49—6)

To all whom it may concern:

Be it known that I, Chauncey E. Waltman, a citizen of the United States, residing in the city of Chicago, county of Cook, and State of Illinois, have invented a new, original, and ornamental Design for a Combination Steam and Dry Iron, of which the following is a specification, reference being had to the accompanying drawings forming a part hereof:

Figure 1 is a perspective view of the combination steam and dry iron showing my new design;

Figure 2 is a side elevational view thereof;
Figure 3 is a top plan view thereof;
Figure 4 is a front elevational view thereof;
Figure 5 is a rear elevational view thereof;
and

Figure 6 is a bottom plan view of the iron.

I claim:

The ornamental design for a combination steam and dry iron, substantially as shown.
